United States Patent Office.

LUKE CHAPMAN, OF COLLINSVILLE, CONNECTICUT, ASSIGNOR TO THE COLLINS COMPANY, OF SAME PLACE.

Letters Patent No. 99,059, dated January 25, 1870.

IMPROVED MILLING-MACHINE.

The Schedule referred to in these Letters Patent and making part of the same.

To all whom it may concern:

Be it known that I, LUKE CHAPMAN, of Collinsville, county of Hartford, and State of Connecticut, have invented a new and useful Improvement in Milling-Machines; and I declare the following to be a full and exact description thereof, reference being had to the accompanying drawings, and to the letters of reference marked thereon, forming a part of this specification.

Figure 1 is a side elevation.

Figure 2 is a plan view.

Figure 3 is a detached view of a milling-tool or cutter.

Like letters indicate like parts in all the figures.

This milling-machine is intended for milling a rounded or other surface upon the side of a bar of metal, for cutting a screw-thread upon such rounded surface, and for similar purposes. I will show its action in the manufacture of my patent wrench-bar.

The letter *a* designates the frame of the machine, supported upon four legs, one at each corner, two of which, *b b*, are seen in fig. 1.

At one end of the frame is the adjustable carriage *c*, which is moved lengthwise of the frame by the regulating-screw *d*, and crosswise by the screw *e*.

On the carriage *c* are fastened the stanchions *f f*, which support the shaft *g*, driven by a belt upon the wheel *h*.

At the other extremity from the wheel *h* is fixed the cutter or milling-tool *i*, the character of which may be varied for different purposes.

It will be readily understood that by means of the two regulating-screws *d* and *e*, the cutter *i* can be brought into different positions, as desired.

The letters *j j* indicate two stanchions rigidly fixed to the frame *a*, having, at their tops, bearings for the shaft *k*, which is rotated, when desired, by the handle *l*.

The end *m* of this shaft has a screw cut upon it, corresponding to the thread it is desired to cut upon the wrench-bar *n*, and this screw fits into a female screw in the bearing *x*, so that, when the handle *l* is rotated, the whole shaft *k* is moved backward or forward.

At the other end of the shaft *k* is a device for temporarily fastening a wrench-bar to the shaft, in such

shape that the centre of the wrench-bar and the centre of the shaft shall be about in the same line.

A screw, *o*, pressing down upon the plate *p*, furnishes the necessary grip for keeping the wrench-bar secure in its place.

Now, a cutter, like that shown in fig. 3, being fastened upon the shaft *g*, the shaft being meanwhile driven by power, and the cutter having been brought into proper position by means of the regulating-screws *d* and *e*, the shaft *k* is rotated by means of the hand upon the handle *l*, or its equivalent, through about a quarter of a circle; and the side of the wrench-bar next the cutter will be milled off into a curved or rounded surface.

Now, substitute the cutter *i* for the one shown in fig. 3, repeat the operation just described, and a thread will be cut upon the rounded surface. It will be observed that the cutter *i* is the same as the cutter shown in fig. 3, except that it has grooves running around it at regular intervals, corresponding to the pitch of the screw *m*. They need not run obliquely around, but will do the work as well if they run straight around.

So far, I have only described the application of this machine to the manufacture of wrench-bars. It is obvious that it is quite as applicable to numerous other and similar purposes.

I claim, as my invention—

The shaft *k*, combined with the grasping-device, in the manner and for the purpose described.

Also, the combination of the shaft *k*, the said grasping-device, and the handle *l*.

Also, the shaft *k*, and grasping-device, in combination with the screw at *m*, and its corresponding female screw.

Also, the shaft *k*, and the grasping-device, in combination with the milling-tool *i*, or any other milling-tool or device which can be used in its place.

Also, the holding-device on the end of shaft *k*, constructed, arranged, and operated as set forth.

LUKE CHAPMAN.
